US0D1036651S

(12) **United States Design Patent** (10) **Patent No.:** **US D1,036,651 S**
(45) **Date of Patent:** **** Jul. 23, 2024**

(54) **DEVICE FOR NASAL SPRAYS**

(71) Applicant: **APTAR FRANCE SAS**, Le Neubourg (FR)

(72) Inventor: **Matthieu Baillet**, Rouen (FR)

(73) Assignee: **APTAR FRANCE SAS**, Le Neubourg (FR)

(**) Term: **15 Years**

(21) Appl. No.: **29/818,781**

(22) Filed: **Dec. 10, 2021**

(30) **Foreign Application Priority Data**

Jun. 11, 2021 (EM) 008574297-0002

(51) **LOC (14) Cl.** **29-02**

(57) **CLAIM**

The ornamental design for a device for nasal sprays, as shown and described.

DESCRIPTION

FIG. 1 is a perspective view of the device for nasal sprays according to the invention,

FIG. 2 is a front view thereof,

FIG. 3 is a rear view thereof,

FIG. 4 is a right side view thereof,

FIG. 5 is a left side view thereof,

FIG. 6 is a top view thereof; and,

FIG. 7 is a bottom view thereof.

The broken lines depict portions of the device for nasal sprays that form no part of the claimed design.

1 Claim, 7 Drawing Sheets
